UNITED STATES PATENT OFFICE.

HOWARD L. PAGE, OF CHICAGO, ILLINOIS.

TAPE SOUND RECORD.

Original application filed September 12, 1921, Serial No. 500,012. Divided and this application filed May 11, 1922. Serial No. 560,221.

To all whom it may concern:

Be it known that I, HOWARD L. PAGE, a citizen of the United States, residing at Chicago, in the county of Cook and State of Illinois, have invented a certain new and useful Improvement in Tape Sound Records, of which the following is a specification.

This invention relates to machines of the phonographic type for reproducing recorded sound.

The object of the invention is to provide a tape sound record usable in reels, like a motion picture film, for the purpose of being passed through a machine which will 15 operate on the record and thereby produce in audible sounds the same sounds which were originally spoken into a recording machine. The device of this invention is primarily designed for use in the machine of 20 my prior application, Serial No. 500,012, filed September 12, 1921, of which this is a division.

The object of this invention is to provide a record of this class which can be easily 25 made in the proper machine from which commercial duplicates can be readily made and which will in service accurately deliver to the reproducing machine the exact vibrations originally sent to the record through 30 the recording machine.

The invention consists in mechanism for attaining the foregoing and other objects and which possesses the special features and details which will be hereafter more fully 35 set forth in the specification and claims.

In order to fully disclose the record of this invention, the drawings and specification will fully set forth the method of manufacture of the record from an original photographic negative produced by sound waves 40 entering the recording machine of said prior application and the apparatus for using the record in the reproduction of sound.

For the purpose of insuring identity of 45 this divisional application with the original application, Figures 12 to 27 of the original application are here reproduced with only the numerals indicating the figures properly reduced. All letters of reference are those 50 of the original application.

Referring to the drawings, in which like numerals designate the same parts throughout the several views:

Figure 1 shows a piece of a record film 55 produced, for instance, by the machine of

said original application and indicates the manner in which a pointed pencil shaped beam of light, fully described in said application, has operated to produce an accurate sound record on the film.

Figure 2 is a sectional detail view on the line 2—2 of Figure 1 of the first sound photograph as actually produced on the film of the machine.

Figures 3, 4, 5, 6, 7, 8, 9, 10 and 11 show successive steps in the method or process of converting the undeveloped film record of Figure 1 into the commercial record of Figure 11, Figures 6 and 9 showing mechanical means for treating certain of the intermediate records; Figures 7 and 8 being sections on the corresponding lines of Figure 6 and Figures 10 and 11 being sectional views on correspondingly numbered cross lines of Figure 9.

Figure 12 shows the reproducing machine by which a commercial sound record of the type produced by the machine of said prior application is used to reproduce the original sounds. This figure is a side view of the 80 mechanism of Figure 13.

Figure 13 is a plan detail view of the mechanism of Figure 12.

Figure 14 is a detail of the pivot mechanism for the record reproducing bar taken 85 from approximately the points indicated by the arrows at 14—14 of Figure 13.

Figure 15 is an enlarged detail view of the reproducing bar showing the manner in which it contacts the reproducing record in 90 transmitting what is on it into audible sound.

Figure 16 shows an electric circuit and mechanism inserted therein by which the reproducing apparatus of this invention may 95 be used to produce the actual sounds which are on the record at any distance from the main machine, either a few feet or many miles.

Assuming, for the purposes of this divisional case, that the operator has by the use of any machine produced the negative record 54 in which 174 indicates the exposed parts, 176 the unexposed parts and 172 the juncture between them, and desired to produce the product of this invention, the operator now takes undeveloped film 54, shown in Figure 1, and gives it an ordinary photographic development, as shown in exaggerated section in Figure 2, viz.: a film body 110

54, an exposed or opaque portion 174, and a clear portion 176 of the same thickness as the opaque portion 174. The two portions 174 and 176 contact each other in line 172. 5 The operator now takes this developed film and turns it top for bottom and applies it as shown in Figure 3 to another parallel second film body 178 having on its lower surface, which is not in contact with any 10 part of the first film, a coating of a gelatin emulsion sensitized by the use of potassium bichromate or other suitable alkali bichromate as well understood in the photographic art. The operator now prints in the ordinary 15 manner from the top through the two films 54 and 178, with the result that portion 180 of the gelatin emulsion which is below opaque portion 174 of film 54 is unaffected by light and will wash off, while portion 182 of the gelatin emulsion which is below clear portion 176 of the film 54 is visibly and actively affected by light and therefore caused to adhere permanently to the film 178. A very important feature occurs 20 at this point—the gelatin emulsion portion 182 is affected by the light along its height in proportion to the nearness of the portion affected to the light. In other words, the upper portion of the emulsion 25 part 182 which is on top as viewed in Figure 3 and nearest the film 176 is more forcibly affected by the light and therefore most actively caused to adhere to the film 178 while portions lower down in the coating 30 182 are less actively affected by light and the lower portions at the bottom may not really be affected at all, but be the latter as it may, the fact that the emulsion is on the bottom of the film 178, when printing 35 takes place, insures that this printed section 182 will closely adhere to the film 178 and not wash away when the operator places the printed film 178 in the bath 184 as shown in Figure 4. In this bath 184, all of gelatinized portion 180 washes away and possibly some parts of the bottom portion of gelatinized printed portion 182 wash away 40 leaving the film 178 when it is turned over from the bath position, as shown in Figure 45 5, with gelatinized member 182 adhering thereto and the rest of the film clear. 50

Gelatinized member 182 is in a very soft swelled condition due to the fact that it has just been in the bath and it is capable when 55 it dries of shrinking to the form 182^a, Figure 8, where it is too thin for actual use as a sound reproducing record and it is therefore necessary to make another film while the gelatinized record 182 is still swelled. 60 This is accomplished by placing the film of Figure 5 in the machine of Figure 6 and forming thereon the third record.

The machine of Figure 6 includes a delivery roll 186, a receiving roll 188 for the film, a table 190 over which the film passes,

adjustable trough edges 192 and 194 between which the film passes, a heated material tank 196 warmed by the electric coil 198 delivering record material through a spout 200 onto the table 190; a scraper 202 adjustable 70 vertically on a rod 204 by means of a set screw 207. The table may, if desired, be provided with a cooling coil 206, to keep the parts at proper temperature.

In the operation of this machine, the film 75 body 178 and soft spongy gelatinized member 182 is passed over the table 190 between the members 192 and 194 and under the spout 200. Tank 196 is filled with a material which when heated can flow down onto 80 the film 178 on table 190 and fill up the space at the side of gelatinized portion 182 without injuring the gelatin. It should also be a material which when cooled does not materially shrink and which is hard enough 85 to stand the forming of a final record from it when it is again run through the machine of Figure 6 or one similar thereto as shown in Figure 9 for this purpose. Such a material is found to be gutta percha and 90 wax and asphaltum in approximately equal parts. The asphaltum makes it set when cold, the gutta percha makes it flexible and the wax gives it body and holds the other parts together. As this material passes 95 down the spout 200 onto the table it fills in the space on the film 178 not occupied by gelatin member 182 and forms the record 210 appearing in Figures 6, 7 and 8, and adheres firmly to the film 178. As the 100 product of the machine of Figure 6 is wound onto the reel 188, the whole thing dries and gelatinized member 182 shrinks down to the form 182^a, heretofore referred to, leaving the unshrinkable member record 105 210 as the outstanding feature of the film.

This record just described and shown in section in Figure 8 is kept as the master record from which reproducing records for use in a reproducing machine may be made when 110 and as desired. When it is desired to make such a reproducing record this master record is run through the machine of Figure 9 which differs only from that of Figure 6 in that additional film carrying rolls 212 115 and 214 are provided above the machine, said rolls being adapted to have gummed paper 216 pass from roll 212 to roll 214 over a suitable moistening roll 218 and thence over a pressing roller 220 located immediately above the table 190 where it can force the paper 216 into contact with record member 222 formed on the table by feeding a mixture of liquid celluloid from tank 196 down onto the moving film 178 and between 120 record 210 and the guide 194. In other respects, the machine operates just as the machine of Figure 6 does, the operator—if he likes—manipulating a rolling pin 226 to be sure that the celluloid material 222 ac- 130

curately fits into place in register with the record 210. When the machine carries the gummed paper record 216 down into contact with the moving film 178 carrying the 5 celluloid record 222, the paper adheres to this celluloid 222 and forms the finished record which is seen in Figure 9 passing upward from roller 220 to roller 214.

This finished record has a very hard and 10 strong record portion 222 of celluloid and a very light and inexpensive carrier portion 216 of paper. It can be readily replaced without much expense by running the same celluloid or other celluloid through the 15 machine of Figure 9 in conjunction with the record 178-210.

In the whole productive operation, the only point requiring excessively competent high skilled labor is the making of the one 20 master record while the gelatin portion 182 is spongy; at all other points, everything is hard and accurate and it is not easy to have trouble.

When it is desired to use the final record 222-216 to produce audible sound, it is run 25 through a reproducing machine of the type shown in Figures 12 and 16, inclusive. A preferred form of the device is shown conventionally mounted inside of a case 228 30 provided with record carrying reels 230 and 232 between which the record may be passed over driving rollers 234 suitably power actuated and an intermediate roller 236. At one side of the case there is a large opening 238 35 over which fits the resonator 114 heretofore referred to, differing from the one of the producing machine only in that an ordinary reproducing disc 240 of metal, mica or any other commercial form of material is 40 substituted for the one of gold beaters skin 120 heretofore referred to. This resonator carries a frame 244 similar to frame 182 carrying soft rubber pivot bearings 242 between which is journaled a shaft 45 246 of a reproducing rod 248 adapted to contact the line 172 of the record 222 at an angle thereto as shown in detail in Figure 15 and be held in contact therewith by a spring 250 as shown in Figure 13. The 50 soft rubber bearings 242 are important in absorbing undue vibrations which might affect the reproducer. This rod 248 extends transversely of the record 222-216 and completely across it and the record is located 55 near the end of the rod so that there is ample opportunity for the rod to follow all of the small movements and variations of the curved line 172 as the record passes under the rod thereby insuring transmission of 60 those variations from the rod 248 through a connecting rod 252 attached to the diaphragm 240 with the result that all the variations in the record 222 are transmitted to the diaphragm and consequently into the 65 air as sound, such sound being, because of

the accuracy of the machine and the methods followed an exact reproduction of the sounds initially delivered into the resonator 114 of the receiving machine.

Particular attention is called to Figure 15 70 which shows exactly how the rod 248 travels only on the edge 172 of record 222 as distinguished from contacting the upper surface of the thickened portion 222 and thereby insuring that the record undulations of 75 line 172 are all accurately transmitted to the reproducer.

It is, of course, to be understood that the markings of line 172 in the various drawings are very much exaggerated for purposes of illustration but records made by this method do in fact vary in the same way that they are illustrated and the machine does produce in actual practice the sounds recorded. 85

Figure 16 shows a modified form of construction in which the reproducing bar 248 instead of operating directly upon the diaphragm 240, operates in conjunction with a transmitting magnet 254 connected in circuit 90 through the wires and electrical mechanism 256 with a reproducer magnet 258 adapted to operate the diaphragm 240^a of a distant resonator 114^a. Under this construction the members 240^a and 248 may be miles apart 95 without affecting the result.

Attention is called to the fact that the pivotal point 134 of mirror 136 is such that the pencil shaped beam of light 170^a extends directly across the path of travel of 100 the film 54 and that the mirror and diaphragm are so proportioned that the point of this beam of light, produced by angular point 168 in the partition 64^a, never under any circumstances leaves the film thereby 105 insuring a line 172 of some sort always on the film. The slot 144 is made of such a length that regardless of the variations in the position of the point of the pencil on the film the lighted portion always extends to 110 the lower edge of the film as illustrated in Figure 1 with the result that the light affected area 174 always extends solidly to the edge of the film thereby insuring a solidly and completely exposed area 174 on 115 that side of line 172.

By the use of the pin slot connections 110 resonators carrying different sized diaphragms 120 may be substituted one for the other if desired to vary the amplitude of the 120 vibrations of the diaphragm and consequently the amount of vertical vibration in the line 172 of the record.

Having thus described my invention, what I claim as new and desire to secure by Letters Patent is:

1. As an article of manufacture, a carrier formed with a flat surface, having thereon a raised portion, said raised portion having sound record indentations in one edge and 130

- extending in varying widths cross-wise of the carrier, the portion being of sufficient height above the strip to mechanically affect a transmitting device engaging said indentations.
2. As an article of manufacture, a carrier formed with a flat surface and having thereon a raised portion, said portion having sound record indentations in one edge at right angles to the surface of the carrier and extending in varying widths cross-wise of the carrier, the portion being of sufficient height above the strip to mechanically affect a transmitting device engaging said indentations.
3. An article of manufacture, a carrier formed with a flat surface, having thereon a raised portion, said raised portion having sound record indentations in one edge and extending in varying widths cross-wise of the carrier, the portion being of sufficient height above the strip so that the indentations can mechanically affect a lever pivoted at one side of the carrier and bearing on said indentations.
4. As an article of manufacture, a carrier formed with a flat surface and having thereon a raised portion; said portion having sound record indentations in one edge at right angles to the surface of the carrier and extending in varying widths cross-wise of the carrier, the portion being of sufficient height above the strip so that the indentations can mechanically affect a lever pivoted at one side of the carrier and bearing on said indentations.

In witness whereof, I have hereunto subscribed my name.

HOWARD L. PAGE.
